CRYSTAL OSCILLATOR CIRCUITS

Donald E. Norgaard, Scotia, N. Y., assignor to
General Electric Company, a corporation of
New York

Application April 27, 1943, Serial No. 484,733

18 Claims. (Cl. 250—36)

1

My invention relates to oscillator circuits and in particular to piezo-electric crystal controlled oscillator circuits. It is well known that a quartz crystal by itself exhibits the electrical properties of both a series resonant circuit and a parallel resonant circuit and, customarily, is represented electrically as a series circuit of inductance, capacitance and resistance, this series circuit being shunted by a capacitance. When supported in a holder, the combination of the holder and crystal likewise exhibits the electrical properties of both series and parallel resonance, the holder appearing as additional capacitance in shunt to the above-mentioned circuit. It is an object of my invention to provide an improved crystal controlled oscillator circuit in which the crystal operates at its series resonant point.

Another object of my invention is to provide an improved oscillator circuit which is substantially free from any shift in frequency as the tuning is adjusted.

A further object of my invention is to provide an improved crystal controlled oscillator circuit in which the frequency of oscillations produced is substantially unaffected by either the capacity of the crystal holder or the intensity of the operating potential applied to the associated vacuum tube circuit.

One of the features of my invention is the employment of a piezo-electric crystal, operating at its series resonant point and connected between the input and output circuits of an electron discharge device in an oscillating circuit, as feedback means to sustain oscillations of the circuit as well as to control the frequency of such oscillations.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing, in which Fig. 1 represents a crystal oscillator circuit constructed according to my invention and Figs. 2 and 3 are modifications of the circuit of Fig. 1.

Referring to Fig. 1, I have shown a crystal oscillator circuit comprising an electron discharge device 10 having an anode 11, a cathode 12, and a control electrode 13. A tuned input circuit comprising a fixed inductance 14 and a variable capacitance 15 is connected between control electrode 13 and ground through a grid leak resist-

2

ance 16 having a condenser 17 in shunt therewith. Cathode 12 of device 10 is connected to ground through a cathode biasing resistance 18. Anode 11 is supplied with operating potential from any suitable source, such as the battery 20 through a decoupling resistance 21, and a capacitance 22 is connected between the anode 11 of the oscillator circuit and ground to by-pass alternating currents from the anode circuit of device 10.

As means to sustain oscillations in the oscillatory circuit, a piezo-electric crystal 25, supported in a suitable holder 26, is connected between cathode 12 and a fixed point, or tap, 27 on inductance 14.

In the operation of the crystal oscillator circuit thus described, capacitance 15 is adjusted to resonate with inductance 14 substantially at the series resonant frequency of the crystal 25. As pointed out previously, it is well known that a piezo-electric crystal exhibits the electrical properties of a series resonant circuit, as well as a parallel resonant circuit, the series resonant point being substantially unaffected by adjustment of the crystal holder spacing or the capacitance of the crystal holder and associated circuits, whereas the parallel resonance point of the crystal is a function of these parameters. In the circuit of Fig. 1, since the piezo-electric crystal 25 exhibits a sharp series resonant characteristic, the amount of feedback from the output circuit of the device 10 to the input circuit is a function of frequency. This feedback is greatest when the impedance of the crystal is lowest, that is, when the crystal is operated at its series resonant frequency. Since the inductance 14 and capacitance 15 are tuned approximately to the same frequency as the crystal, the loading effect of this tuned circuit on the device 10 is small at this operating frequency. Also, since the feedback path from the cathode to the control electrode through crystal 25 is much more sharply tuned than the tuned circuit composed of elements 14 and 15, the crystal 25 has a controlling effect on the frequency of oscillations generated in the oscillating circuit.

In order to sustain oscillations in the circuit thus described the loop gain through the feedback circuit is adjusted to have an average value of unity, any other value resulting in either rising or falling values of oscillation, until stable conditions are reached. The loop gain of this oscillatory circuit is automatically maintained at an average value just sufficient to sustain stable oscillations of a certain desired strength by means

of the grid leak resistance 16 and the condenser combination 17.

Also, when the current in grid leak resistor 16 is zero at the initiation of operation enough loop gain is provided in the oscillatory circuit to permit oscillation to start. To this end, the cathode biasing resistance 18 is of such a value as to allow oscillations to build up to a substantially fixed value before regulation of gain by the grid leak resistance 16 is started, the fixed value being such that a loop gain of greater than unity is attained when elements 14 and 15 resonate at substantially the frequency of the crystal.

In the modification of the oscillatory circuit shown in Fig. 2, an electron discharge device 30 of the pentode type is employed. The connections of the input circuit between the control electrode 31 and the cathode 32 are the same as are shown in the circuit of Fig. 1 and corresponding parts of the two circuits have been designated by corresponding reference numerals. The screen electrode 33 of the device 30 functions as an anode for the oscillatory circuit. It is supplied with operating potential from the battery 20 through a decoupling and voltage dropping resistance 34 and is by-passed to ground for alternating currents by means of a capacitance 35. The anode 36 may be supplied with operating potential from the battery 20 through a load circuit 37. The suppressor grid 38 is connected directly to ground, instead of to the cathode, to prevent coupling between the cathode and anode 36 due to the capacity between the suppressor grid 38 and anode 36.

In the operation of the oscillatory circuit of Fig. 2, the output currents flowing between the anode 36 and cathode 32 vary in frequency in accordance with the oscillations which are developed between the screen electrode 33, operating as an anode, and cathode 32. As in the operation of the circuit of Fig. 1, the loop gain of the oscillatory circuit of Fig. 2 is automatically maintained at an average value of unity, that is, a value just sufficient to sustain stable oscillations, by means of the grid leak resistance 16 and capacitance 17. The cathode biasing resistance 18 is of such value that the bias provided by the cathode current flowing therethrough allows the oscillations to build up to a substantially fixed value before the grid leak resistance 16 functions to regulate the gain of this portion of the circuit. The tuned circuit 14, 15 is adjusted to resonate substantially at the series resonant frequency of the crystal 25 so that the loop gain of the oscillating circuit, the value of which is a function of frequency, may be greatest at the series resonant frequency of the crystal and of such value at this frequency that oscillations are sustained.

In Fig. 3, I have shown another modification of my oscillator circuit in which the tuned input circuit connected between the control electrode 13 of electron discharge device 10 and ground comprises an inductance 40 having in shunt therewith the serially connected capacitances 41 and 42. The inductance 40 may be variable in order to adjust the tuning of the circuit, or all of the reactance elements may have preselected values such that the tuned circuit resonates substantially at the series resonant frequency of the crystal 25. The piezo-electric crystal 25 is connected between the cathode 12 of the device 10 and the common point of capacitances 41 and 42 to function as a feedback circuit between the input and output circuits of device 10. Since the tuned input circuit operates at the series resonance fre-

quency of crystal 25, this feedback circuit exhibits a sharp resonant characteristic. In the oscillatory circuit, the values of capacitances 42 and 41 are adjusted so that the loop gain of the oscillating circuit may be of such value at the series resonant frequency of the crystal that oscillations are sustained. In all other respects this circuit functions essentially the same as the circuit of Fig. 1.

It is seen that the crystal oscillator circuit of my invention, by operating at the series resonant point of the crystal, provides oscillations which are substantially free from frequency shift during tuning adjustments. The frequency of oscillations produced is substantially unaffected by either the capacity of the crystal holder 26 or the intensity of the operating potential applied by means of source 20. The resultant oscillatory circuit, therefore, is both simple in construction and, because the feedback path between the input and output circuits is tuned sharply by the crystal to the series resonant frequency of the crystal, is stable in operation.

While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. An oscillatory circuit comprising an electron discharge device having an anode, a cathode, and a control electrode, a tuned circuit connected to said control electrode, an impedance connected between said tuned circuit and said cathode, and feedback means comprising a piezo-electric crystal connected between said cathode and a fixed point on said tuned circuit, said tuned circuit being tuned substantially to the series resonance frequency of said crystal.

2. An oscillatory circuit comprising an electron discharge device having an anode, a cathode, and a control electrode, a tuned circuit connected between said control electrode and a point of fixed potential, an impedance connected between said cathode and said point, and feedback means comprising a piezo-electric crystal connected between said cathode and a fixed point on said tuned circuit, said tuned circuit being tuned substantially to the resonance frequency of said crystal.

3. An oscillatory circuit comprising an electron discharge device having an anode, a cathode, and a control electrode, a tuned circuit connected between said control electrode and a point of fixed potential, an impedance connected between said cathode and said point, and feedback means comprising a piezo-electric crystal connected between said cathode and a fixed point on said tuned circuit, said tuned circuit being tuned substantially to the series resonance frequency of said crystal.

4. An oscillatory circuit comprising an electron discharge device having an anode, a cathode, and a control electrode, an inductance having a capacitance in shunt therewith connected to said electrode, an impedance connected between said tuned circuit and said cathode, and feedback means comprising a piezo-electric crystal connected between said cathode and a fixed point on said inductance, said inductance and said capacitance having such values as to resonate substantially at the series resonance frequency of said crystal.

5. An oscillatory circuit comprising an electron discharge device having an anode, a cathode, and a control electrode, an inductance having a capacitance in shunt therewith connected between said control electrode and a point of fixed potential, an impedance connected between said cathode and said point, a by-pass capacitance connected between said anode and said point, and feedback means comprising a piezo-electric crystal connected between said cathode and a fixed point on said inductance, said inductance and said capacitance having such values as to resonate substantially at the series resonance frequency of said crystal.

6. In an oscillator, the combination of an electron discharge device having an anode, a cathode, and a control electrode, an input circuit connected to said electrode, said circuit comprising a serially connected resistance and inductance, a second resistance connected between said inductance and said cathode, feedback means comprising a piezo-electric crystal connected between said cathode and a tap on said input circuit, and means for resonating said inductance substantially at the series resonance frequency of said crystal.

7. In an oscillator, the combination of an electron discharge device having an anode, a cathode, and a control electrode, a by-pass capacitance connected between said anode and ground, a resistance connected between said cathode and ground, an input circuit connected between said control electrode and ground, said input circuit comprising a serially connected resistance and inductance, feedback means comprising a piezo-electric crystal connected between said cathode and a tap on said input circuit, and means for resonating said inductance substantially at the resonance frequency of said crystal.

8. In an oscillator, the combination of an electron discharge device having an anode, a cathode, and a control electrode, a by-pass capacitance connected between said anode and ground, a resistance connected between said cathode and ground, an input circuit connected between said control electrode and ground, said input circuit comprising a serially connected resistance and a pair of capacitances, feedback means comprising a piezo-electric crystal connected between said cathode and a point between said capacitances, and means for resonating said capacitances substantially at the resonance frequency of said crystal.

9. A piezo-electric crystal oscillation generator comprising an electron discharge device having an anode, a cathode, and a control electrode, an input circuit connected between said control electrode and cathode, a by-pass capacitance connected between said anode and said cathode, said input circuit including a tuned circuit, and feedback means connected between said cathode and said input circuit, said means comprising a piezo-electric crystal, said tuned circuit being adjusted to resonate at substantially the series resonance frequency of said crystal, and said feedback means presenting a low impedance between said cathode and said input circuit to currents of said frequency.

10. In an oscillator circuit, the combination of an electron discharge device having an anode, a cathode, and a control electrode, a circuit connected between said anode and ground, a resistance connected between said cathode and ground, an input circuit connected between said control electrode and ground, said input circuit comprising

ing a serially connected resistance and inductance, feedback means comprising a piezo-electric crystal connected between said cathode and a tap on said inductance, and a capacitance connected across said inductance, said capacitance being of such value as to resonate said inductance substantially at the resonance frequency of said crystal.

11. In an oscillator circuit, the combination of an electron discharge device having an anode, a cathode, and a control electrode, a circuit connected between said anode and ground, a resistance connected between said cathode and ground, an input circuit connected between said control electrode and ground, said input circuit comprising a pair of capacitances having a resistance in series therewith, feedback means comprising a piezo-electric crystal connected between said cathode and the common point of said capacitances, and an inductance connected across said capacitances, said inductance being of such value as to resonate with said capacitances substantially at the resonance frequency of said crystal.

12. In an oscillator circuit, the combination of an electron discharge device having an anode, a cathode, a control electrode, and a screen electrode, a tuned circuit connected between said control electrode and a point of fixed potential, an output circuit connected between said anode and said point, a resistance connected between said cathode and said point, a by-pass capacitance connected between said screen electrode and said point, and feedback means comprising a piezo-electric crystal connected between said cathode and a point on said tuned circuit, said tuned circuit being tuned substantially to the series resonance frequency of said crystal, and said point on said tuned circuit being so selected that the current flowing through said feedback means is sufficient to sustain oscillations in said tuned circuit at said frequency.

13. In an oscillator circuit, the combination of an electron discharge device having an anode, a cathode, a control electrode, and a screen electrode, an inductance connected between said control electrode and a point of fixed potential, an output circuit connected between said anode and said point, a resistance connected between said cathode and said point, a by-pass capacitance connected between said screen electrode and said point, and feedback means comprising a piezo-electric crystal connected between said cathode and a point on said inductance, and a capacitance connected across said inductance to form therewith a tuned circuit resonating substantially at the series resonance frequency of said crystal, said point on said inductance being so selected that the current flowing through said feedback means is sufficient to sustain oscillations in said tuned circuit at said frequency.

14. An oscillator circuit comprising an electron discharge device having an anode, a cathode, a control electrode, a screen electrode, and a suppressor electrode, said suppressor electrode being connected to ground and said screen electrode being connected to ground through a by-pass capacitance, a load circuit connected between said anode and ground, a resistance connected between said cathode and ground, a serially connected resistance and inductance connected between said control electrode and ground, feedback means comprising a piezo-electric crystal connected between said cathode and a tap on said inductance, and means to resonate said inductance substantially at the series resonant fre-

quency of said crystal, said tap being so positioned that the current supplied to said inductance by said feedback means is sufficient to sustain oscillations therein at said frequency.

15. A stabilized crystal-controlled oscillator comprising electron discharge means including a cathode, a control electrode and an anode, means for supplying electrical heating energy to said cathode, means for applying a relatively high potential to said anode, a parallel resonant circuit comprising an inductor shunted by two capacitors in series, a connection from a point on said inductor to said anode, a connection from another point on said inductor to said control electrode, and a connection including a piezo-electric crystal extending from the mid-junction point of said capacitors to said cathode.

16. A crystal-controlled oscillator comprising electron discharge means including a cathode, a control grid and an anode, means for supplying electrical heating energy to said cathode, means for applying a relatively high potential to said anode, a resonant circuit, means for electrically coupling the grid and anode circuit of said discharge means to produce oscillations in said resonant circuit, and a piezo-electric crystal connected to said cathode and common to said grid and anode circuits.

17. A stabilized crystal-controlled oscillator comprising electron discharge means including a cathode, a control electrode and an anode, means for supplying electrical heating energy to said cathode, means for applying a relatively high

potential to said anode, a parallel resonant circuit comprising an inductive impedance shunted by a capacitative impedance, a connection from a point on said inductive impedance to said anode, a connection from another point on said inductive impedance to said control electrode, and a connection including a piezo-electric crystal extending from a mid-point of one of said impedances to said cathode.

18. A stabilized crystal-controlled oscillator comprising electron discharge means including a cathode, a control electrode and an anode, a parallel resonant circuit comprising an inductive impedance shunted by a capacitive impedance, a connection from a point on one of said impedances to the anode, a connection from another point on the latter impedance to the control electrode, and a connection including a piezo-electric crystal extending from an intermediate point on the latter impedance to the cathode.
